UNITED STATES PATENT OFFICE.

HELEN ALICIA BURT, OF LONDON, ASSIGNOR TO ANTHONY HARRIS, OF MIDDLESBROUGH, ENGLAND.

COIN FREED OR ACTUATED MACHINE.

SPECIFICATION forming part of Letters Patent No. 471,808, dated March 29, 1892.

Application filed May 5, 1891. Serial No. 391,806. (No model.) Patented in England May 19, 1888, No. 7,427; in France July 13, 1889, No. 199,567; in Belgium July 13, 1889, No. 86,976; in Germany July 13, 1889, No. 52,791, and in Switzerland July 30, 1889, No. 1,371.

To all whom it may concern:

Be it known that I, HELEN ALICIA BURT, artist, a subject of the Queen of Great Britain, residing at No. 102 Newgate Street, in the city of London, England, have invented certain new and useful Improvements in Coin Freed or Actuated Machines, (for which Letters Patent in England, No. 7,427, dated May 19, 1888; in France, No. 199,567, dated July 13, 1889; in Belgium, No. 86,976, dated July 13, 1889; in Germany, No. 52,791, dated July 13, 1889, and in Switzerland, No. 1,371, dated July 30, 1889, have been granted in the name of Anthony Harris,) of which the following is

15 a specification.

This invention relates to that class of machines or appliances which are adapted to be operated or rendered operative through the joint action of a predetermined coin introduced into the machine and of an operating device on the exterior thereof.

The object of the invention is to provide such machines or appliances with devices whereby an iron or steel disk, ring, or the like, or an article of smaller diameter than the predetermined coin fraudulently introduced into the machine is prevented from rendering the latter operative, and whereby, also, facilities are offered for the detection of a person making such fraudulent attempt to operate the machine.

The manner of carrying the invention into effect may be fully understood from the following description, reference being had to the accompanying drawings, in which—

Figure 1 is a side elevation, partly in section, showing my improvements, together with the arrangements more immediately connected therewith, the various parts being represented in the positions assumed when the machine is being operated. Fig. 2 is a similar view showing in its normal position a portion of the mechanism represented in Fig. 1. Fig. 3 is a front view of the money-box J, herein-45 after more fully described.

AA are the outer walls of the inclosing case or cabinet of the machine.

A² is a slit or orifice through which a coin may be introduced by the operator into the 50 machine.

The operating mechanism of the machine may be worked by the user (through the intervention of such introduced coin, as hereinafter described) from the exterior of the cabinet by means of a push-handle E or other 55 equivalent operating device.

For the purposes of the present invention any suitable arrangement of mechanism may be employed whereby through the joint action of a predetermined coin introduced into the 60 machine and of an operating device on the exterior thereof the user is enabled to operate (or render operative) the machine. I prefer, however, an arrangement such as that herein set forth, which may be briefly described as 65 follows: The coin is conveyed by means of a tube or slide C C' C², hereinafter described, into a hopper H, Figs. 1 and 2, whence it drops into the money-box J of the apparatus, Figs. 1 and 3. This box J, into which the 70 coin K is conveyed, is formed in the shape of a narrow hopper with sloping ends J' J² (adapted to retain a coin of predetermined size on edge) and vertical parallel sides J³ J⁴. One side J³ is made movable, being preferably 75 hinged or pivoted, as at j, Fig. 1. The fixed side J⁴ of the money-box has an opening j' situated between the sloping ends J' and J², and the hinged side J³ has a similar opening j² exactly opposite the opening j'. The push-handle E is attached to a sliding bar E', the inner end of which rests normally within the hole j' and is adapted when pushed inward to enter the box and pass through the hole j² in its opposite side if the box be empty. The 80 push-bar E' is provided with a returning-spring e, which is inserted between the fixed side J⁴ and a collar e' on the bar. Collars e² e³ control the movement of the bar in either direction. If the bar E' be pushed in after 85 a coin K has been introduced into the box J, it pushes open the hinged side J³ as the coin is retained by the sloping ends J' J² of the box in the position shown in Fig. 3—that is, covering the hole j² in the hinged side. The 90 side J³ is connected by any suitable means, as by a link or lever G', with the mechanism of the machine proper in such a manner that each time the side is thrust open such mechanism is operated or rendered operative. As 95 100

soon as the user releases the bar E' it is forced backward by the spring e and the coin drops down the duct H' into any suitable receptacle, whence the coins may be collected by the owner at intervals. The coin is enabled to drop out of the box on the return of the push-bar by reason of the side J^3 being held momentarily open by a catch-lever M , the outer end of which passes through a slot m in the money-box side, and is provided with a serration or shoulder M' of such a form that it permits the side to open but prevents it from closing. The catch-lever M is pivoted at m' upon a bracket m^2 , carried by the fixed side J^4 of the money-box, and it is provided with an upright arm M^2 , which is struck by the collar e' toward the termination of the rearward movement of the push-bar, so that the catch-lever is tilted up and the hinged side J^3 being released it is closed by a spring J^5 or by its own weight.

To prevent the machine from being rendered operative by an iron disk or the like, one or more magnets are employed, and they are so arranged with reference to the coin-slide that on an attempt being made to operate the machine after the insertion of such iron article the latter, whose movement has been previously arrested by the magnet, is detached from such magnet and diverted into a separate slide and away from the money-box. The magnet, which preferably consists of two or more horseshoe-magnets laid side by side, may either be a fixture, as in Figs. 1 and 2, or it may be movable. When the magnet is fixed, the whole or a portion of the coin-slide is made movable, and when the magnet is movable the coin-slide is made a fixture.

In the machine shown in Figs. 1 to 3 the magnet L is attached to the front wall of the cabinet A and projects upward, with its poles in close proximity to the coin-slide C' , or preferably with its poles projecting into holes l in the bottom of the slide, so that an iron article passing down the slide is retained upon the poles of the magnet. The latter are preferably beveled, as shown, so as to permit of the good coins passing freely over them. The upper part C of the coin-slide is preferably a fixture; but the lower portions C' C^2 are hinged, respectively, at c and c' , so that they may be tilted upward. The lower end of the part C' below its pivot c is connected at n to one end of a link N , whose opposite end is jointed to the upper termination of a rocking lever N' . This lever is pivoted at n' and has its lower forked end engaged by collars e^4 on the push-bar E , whereby at each forward movement of the bar the part C' is tilted into the position shown in Fig. 1, and any article adhering to the magnet L is detached therefrom and falls down a separate duct H^2 onto a dash-pan Q , hereinafter described, or, where such is not used, into a suitable receptacle provided for the above detached articles. The part C^2 of the coin-slide is also tilted upward at the same time, in order to permit the de-

tached article to fall freely into the upper end of the duct H^2 . A cross-bar or guard C^3 is provided on the lower part C^2 of the slide opposite the holes l , for the purpose of preventing an iron article being quickly jerked off the poles of the magnet and over into the part C^2 , whence it could pass into the box J . The extreme lower end of the slide is also turned downward, as at C^4 , to prevent an iron article from getting into the hopper H past the under side of the part C^2 . The upper edge of the part C^2 is made very thin, as at C^5 , so that when lying upon the bottom of the part C' , as in Fig. 2, it offers no impediment to the passage of a coin.

The parts C' and C^2 may be actuated simultaneously as follows: A curved bar or plate P is mounted loosely upon the pivot c of the part C' . The lower end of this bar is provided with a projecting pin p' , which rests against the under side of the part C' near its lower end. The upper end of the bar has an elongated slot p^2 , which engages a pin p^3 on the side of the part C^2 near its upper end. It will thus be seen that each time the lower end of the part C' is depressed by the action of the push-bar the bar P will be moved into the position shown in Fig. 1, and the lower part C^2 of the slide will thereby be tilted. A spring p^4 returns the part C^2 and bar P to their normal positions after the release of the push-bar and the consequent return of the part C' .

P' is a curved bar or plate, which is attached to the upper end of the part C' of the coin-slide and passes through an opening in the fixed part C of the slide. Each time the part C' is tilted by the action of the push-bar the bar P' is placed across the upper part of the slide and prevents the introduction of a coin into the machine after the bar E has been pushed in.

Should a coin, washer, or disk of smaller diameter than that of the predetermined coin be introduced into the machine, it will (if it be not of iron or steel) fall into and pass right through the money-box J into the duct H' , as the sloping ends J^1 J^2 of the box are placed at such a distance apart at their lower ends that they will not uphold a smaller coin, &c. This may be clearly understood from Fig. 3.

To facilitate the detection of a person attempting to operate the machine fraudulently by an iron disk, &c., the following photographic device may be employed: The duct H^2 for spurious iron articles has its exit above a dash-pan Q , which is pivoted at q and is connected by a rearward extension Q' and a link Q^2 to an angle-lever Q^3 , pivoted at q' . R is a very small camera, which is located behind a minute opening R' in the wall of the cabinet and about the height of the operator's face. R^2 is a rod attached to the shutter or other equivalent exposing device adapted when released to give an instantaneous exposure to the sensitized surface in the camera. A spring R^3 , which is introduced between the

bottom of the camera and a collar R⁴ on the rod R², tends always to operate the exposing device by moving the rod R³ downward. This downward movement is prevented by a catch 5 Q⁴, which is carried by the depending arm of the angle-lever Q³ and engages the under side of the collar R⁴. The dash-pan and its connections are held in their normal position by an adjustable balance-weight q⁴. A spurious article falling on the dash-pan Q immediately withdraws the catch Q⁴, releases the exposing device, and effects an instantaneous exposure of the sensitized surface within the camera.

15 a a a are brackets or attachments whereby the various parts of the apparatus are supported within the cabinet A.

The action of the machine may be briefly summed up as follows: A coin of a predetermined kind is inserted at the orifice A² and passes down the slides C C' C² and hopper H into the box J. The handle E is now pushed inward by the user and operates (or renders operative) the machine, as before described. 25 On his releasing the handle E the coin falls down the duct H² and the various parts return to their normal positions. If an iron disk or the like be introduced into the machine, it is diverted by the magnet device, and 30 passing down the duct H² strikes the dash-pan Q, so that the user's photograph is taken by the camera device R. Articles of smaller diameter than the specified size pass right through the money-box J without rendering the machine operative.

35 I declare that what I claim is—

1. In a machine of the kind described, an inclined coin-slide formed wholly or partly of two consecutive lengths hinged at or near 40 their corresponding ends upon approximately horizontal axes, in combination with a magnet adapted to arrest the movement of an iron or steel article in its passage down the upper of said lengths, and a device for simultaneously separating and tilting said lengths at each working of an external operating device, whereby such iron or steel article is diverted from the operating mechanism of the machine, substantially as described.
2. In a machine of the kind described, a coin-slide having a hinged part C' adapted to be tilted at each forward stroke of an external operating device, and a fixed magnet L, having its poles protruding normally, as described, into said hinged part, in combination with a part C², forming the lower portion of said coin-slide and hinged at or near its lower end, and mechanism adapted to separate the lower part C² from the upper part C' and to 55 tilt it simultaneously with the said upper part, whereby an article arrested by the poles of the magnet is detached therefrom and allowed to fall freely out of the coin-slide away from the operating mechanism, substantially as described.
3. In a machine of the kind described, an inclined coin-slide having two consecutive

lengths C' C² hinged at or near their lower ends, a magnet L, located as described with respect to the upper lengths C', and mechanism for tilting said upper length at each operation of an external operating device, in combination with a rocking bar P, having one end adapted to be depressed at each tilting of the said upper length C' and having its opposite end connected with and adapted to elevate the said lower hinged length C², whereby the lengths C' and C² may be separated and tilted simultaneously, substantially as described. 70 80

4. In a machine of the kind described, the magnet L, the upper hinged part C' above the same, the lower hinged part C² normally continuous with the part C', and means for tilting said upper part at each operation of an external device, in combination with the rocking bar P, mounted on the hinge-pivot of the part C', the pin p' on the lower end of said bar and bearing against the under side of the said part C', the pin p³, carried by the upper 85 end of the lower hinged part C² and engaging with a slot p² in the upper end of the said bar P, and a returning-spring p⁴ for said bar and part C², substantially as described.

5. In a machine of the kind described, the combination, with the magnet L, the hinged parts C' and C² of the coin-slide, and means for simultaneously separating and tilting the same at each operation of the external device, of a coin-hopper H below the extremity of the lower part C², a duct H² for iron articles below the extremity of the upper part C', a guard C³ on the part C² opposite the magnet L, and a downwardly-turned lip C⁴ on the lower end of said part C², substantially as and 100 105 for the purposes described.

6. In a machine of the kind described, having an arrangement for diverting spurious articles fraudulently introduced into the machine, a minute photographic camera located 110 with its lens in front of the operator's face, in combination with a dash-pan adapted to be struck by a diverted spurious article, and mechanism connecting said dash-pan with the exposing device of the camera and adapted to 115 instantaneously release or operate the same as soon as the dash-pan is struck, substantially as and for the purpose set forth.

7. In a machine of the kind described, the combination, with an arrangement for diverting spurious articles fraudulently introduced into the machine, of a minute camera R, located as described, a spring-pressed rod R³ R⁴, movable with the exposing device of said camera, an angle-lever Q³, having a catch Q⁴ 120 125 normally retaining said rod against the action of its spring, a counterbalanced dash-pan Q, located in the path of a diverted spurious article, and a link Q², connected at each end, respectively, to the lever Q³ and the dash-pan 130 extension Q', substantially as described.

8. In a machine of the kind described, the combination, with the magnet L, hinged slide C', push-bar E, lever N', link N, and duct H²,

of a counterbalanced dash-pan Q, located below said duct, a minute camera R, located as described, a spring-pressed rod R²R⁴, movable with the exposing device of said camera, a 5 catch Q⁴, retaining said rod against the action of its spring, and means adapted to withdraw said catch and release the exposing device when the dash-pan is struck by an article falling from the duct H², substantially as de-
10 scribed.

In testimony whereof I have signed my name to this specification in the presence of two subscribing witnesses.

HELEN ALICIA BURT.
